UNITED STATES PATENT OFFICE.

PETER KRUSE, OF BROOKLYN, NEW YORK, ASSIGNOR TO E. W. BLISS COMPANY, OF BROOKLYN, NEW YORK, A CORPORATION OF WEST VIRGINIA.

CAN BODY OR TUBE FORMING MACHINE.

Application filed March 18, 1921. Serial No. 453,342.

To all whom it may concern:

Be it known that I, PETER KRUSE, a citizen of the United States of America, residing in the borough of Brooklyn, county of Kings, 5 city and State of New York, have invented certain new and useful Improvements in Can Body or Tube Forming Machines, of which the following is a specification.

This invention relates to machines for 10 forming can bodies or tubes, and aims to provide improvements therein.

The present invention provides a machine in which can bodies or tubes with a reinforced seam (that is, a seam formed by 15 U-ing or channeling the lapped edges of a sheet of metal and flattening the channel so that the sides of the channel inwardly collapse) may be rapidly and expeditiously formed.

20 The invention further provides a novel combination, and sub-combinations, for carrying out the purposes of the invention.

An embodiment of the invention is illustrated in the accompanying drawings, 25 wherein—

Figure 1 is a view, in end elevation, of said embodiment;

Fig. 2 is a view in side elevation, in 30 partial section (the section being on the line 2—2, Fig. 1), of the construction shown in Fig. 1;

Fig. 2^a is a partial sectional view on the line a—a, Fig. 1;

Fig. 3 is an enlarged detail view of certain 35 of the principal operating parts shown in Fig. 1, the view being principally a sectional view;

Fig. 4 is a view similar to Fig. 3, showing the parts in a different position;

40 Fig. 5 is a view showing in somewhat greater detail certain of the parts shown in Figs. 3 and 4, and showing said parts in the final seam-forming position;

Fig. 6 is a detail view, principally in section, on the line 6—6, Fig. 1;

Fig. 7 is a detail view, in side elevation, of the horn;

Fig. 8 is a detail sectional view on the line 8—8, Fig. 6;

50 Fig. 9 is a detail view, in front elevation, of the edge bender shown in Figs. 1 and 2.

Referring to said drawings, numeral 10 designates a horn of any suitable form and

contour, according to the shape of the tubes or bodies to be formed. 55

A piece of sheet metal or the like, X, is placed or wrapped around the horn 10 in such manner that its edges overlap, as shown in Fig. 3. The sheet of metal X is preferably automatically fed and wrapped around the horn, and for this purpose the machine may be provided with a reciprocating feed bar 12, and folders 14, preferably of the wing type. The feed bar or bars 12 are conveniently connected to a cross bar 15 which is reciprocated by means of an oscillating lever 16 connected by means of a link 17 to a crank pin 18 on a disk 19 on one of the main shafts 20 of the machine. 60

The wing folders may be conveniently operated by means of a lever 24, through connecting rods 23, the lever 24 being conveniently connected, by means of a rod 25, to a crank pin 26 on a disk 28 on another of the main shafts 30 of the machine. 65

Numeral 35 designates an outside former, and 70 36 an inside former, which parts coact to U or form into a channel the lapped edges of the sheet of metal. The inside former is conveniently mounted upon the horn, and the outside former is conveniently on a part 38 mounted upon a slide 39, movable toward and from the horn, movement to the slide 39 being conveniently imparted thereto by means of a rod or rods 41 engaging, by 75 means of rollers 42, cams 43 conveniently on the main shaft 20. The ends of the rod or rods 41 are conveniently forked, as indicated at 44 (Fig. 2), and straddle the shaft 20 (or a collar thereon), and thereby guide the 80 said rod or rods 41. For compelling the rod or rods 41 to closely follow the cam, a spring or springs 45 may be attached to the said rod or rods 41. The part 38 may be adjustably mounted in the slide, by means 85 of screw-threads 48 (Figs. 1 and 3). Lock nuts 49 may serve to hold the part 38 in position on the slide.

Means are provided for compressing the U-ed or channelled portion formed in the 100 lapped edges of the sheet. These means are conveniently a hammer 50, in the form of a plate corresponding in the length to the seam, and conveniently working through the outside former 35. The hammer or plate 50 105 is conveniently attached to a block 52, and

this block 52 conveniently abuts a spring-pressed block 54, the springs 55 tending normally to press and resiliently hold the plate or hammer 50 as projecting slightly beyond 5 the outside former. For imparting a hammer stroke or movement to the plate or hammer 50, a plunger 57 may be provided, this plunger 57 conveniently working within the part 38 and striking against the under side 10 of the block 54 which abuts the block 52 carrying the hammer 50. Movement is conveniently imparted to the plunger 57 by means of an eccentric strap 59 surrounding an eccentric 60 on the main shaft 20. 15 The inside former 36 is adapted to recede during the hammer stroke of the hammer 50, and to this end the inside former is conveniently formed with cams or inclined planes 63 coaxing with a cam or inclined planes 61 20 on a slide 62, the slide 62 being conveniently mounted and guided in the horn 10. The slide 62 is conveniently moved back and forth by means of a lever 65 connected thereto by a short link 66, the lever 65 being actuated by an arm 67 having a pin or roller 68 engaging a cam groove 69 in a disk 70 conveniently mounted upon the main shaft 20. The arm 67 is conveniently forked, as indicated at 72, and straddles the shaft 20 25 30 or a collar thereon, in such manner as to be guided on said shaft.

The wing folders conveniently comprise a pair of pivoted arms 80 having flexible tips or portions 81 thereon for engaging and 35 wrapping the sheet of metal around the horn. These tips 81 are conveniently pivoted to the arms 80, as indicated at 82, and resiliently pressed around said pivots by means of springs 84 (Fig. 3), the movement 40 of the said tips 81 around their axes 82 being limited by means of headed screws 86.

For holding the wrapped sheet of metal during a part of the movement away from the horn, of the wing folders 14, means, 45 such as resilient blocks 90, may be provided. These blocks 90 are conveniently carried in the arms 80, and are resiliently pressed toward the horn by means of springs 92, the inward movement being conveniently limited by means of nuts 93 on screws 94.

The horn is conveniently provided with collapsible or resilient portions 100. These portions collapse or yield to reduce the perimeter of the horn, in order to facilitate the 55 discharge or sliding off of the formed bodies or tubes. These portions 100 are conveniently in the form of dovetail strips fitting corresponding grooves in the horn, and pressed outwardly by means of springs 101.

60 For facilitating the wrapping of the sheet around the horn, the machine, at a position in advance of the horn and wrapping station, may be provided with means, such as a roller 110, and an anvil 111, adapted to bend 65 slightly the edge of the sheet which is folded

in against the horn ahead of the other edge. This position of the lapped edge portions is clearly shown in Fig. 3.

For facilitating the entrance of a sheet of metal between the horn 10 and a ledge 115, 70 the horn may be mounted upon a slide 116, the slide 116 being adapted to be moved very slightly from the ledge 115 as the sheet is fed onto the horn, this movement of the slide being conveniently effected by means 75 of a bell crank lever 120 connected to the slide by link 121, and receiving motion from a cam 122 conveniently on the main shaft 20. This cam and the bell crank lever is shown in detail in Fig. 2^a of the drawings. 80

Operation: A sheet of metal is wrapped around the horn 10, with its edge portions overlapping, as shown in Fig. 3. The wrapping is conveniently automatically done by means of wing folders 14, which, when the 85 sheet is fed to the horn position, as they swing together, carry the sheet (X, Fig. 1) with them and wrap the sheet around the horn. Previously to reaching the horn position, one edge portion of the sheet is conveniently bent, as by means of the roller and anvil 110, 111. This bent edge enables the edges to lap without interference. 90

The inside former 36 is held in projecting position, as shown in Fig. 3. The slide 39 carrying the outside former 35 approaches during the wrapping movement, and as the wing folders start to move away, the overlapped edges are conveniently held by the resilient hammer 50 which bears against the 100 overlapped edges of the wrapped sheet X. Moreover, the overlapped edges of the sheet, during this initial movement away, of the wing folders, are held from moving apart by means of the resilient blocks 90, which 105 continue to press the sheet against the horn during the initial movement away of the said wing folders. During this initial movement away, of the wing folders, the inside former starts its bending action upon 110 the lapped edges of the sheet, and forms a channel or U-ed portion of the length of the tubular body former by the wrapped sheet. During this bending or U-ing action, the resilient hammer 50 yields, and when the outside former 35 reaches the limit of its movement toward the horn, the lapped edges of the sheet have the form shown in Fig. 4. The slide 62 at about this time is given a quick movement, lifting the inside former 120 out of the channel or U-ed portion of the sheet. The plunger 57 thereupon moves into contact with the block 54 and presses or impels it, so as to cause the hammer 50 to

strike or compress the U-ed portion of the 125 lapped edges of the sheet, and, the inside former being withdrawn, the parallel walls of the U or channel collapse inward, and a seam, such as shown in Fig. 5, is formed. The outside former 35 thereupon moves 130

away from the horn, carrying with it the hammer 50, and the can body may then be removed or ejected from the horn. To facilitate the removal, the collapsible or resilient horn sections 100 yield, reducing the perimeter of the horn and allowing the tube or can body formed from the wrapped sheet X to be easily removed from the horn.

The invention may receive other embodiments than that herein specifically illustrated and described, and parts and sub-combinations may be used out of the specific combinations referred to.

What I claim is:—

15 1. An apparatus of the character described, comprising a horn around which a piece of sheet metal is adapted to be wrapped with ends overlapping, an inside former and an outside former adapted to bend the overlapped portions of the piece of sheet metal into U or channel form, means for compressing said U-ed overlapped portions while held by said outside former, and means for moving said inside former out of 20 the U-ed portion to permit the inward collapse of the U-ed portions, and thereafter holding said inside former to act as an anvil while said compressing means presses said collapsed portions on said anvil to complete the formation of the locked seam.

25 2. An apparatus of the character described, comprising a horn around which a piece of sheet metal is adapted to be wrapped with ends overlapping, an inside former and an outside former adapted to bend the overlapped portions of the piece of sheet metal into U or channel form, means for compressing said U-ed overlapped portions while held by said outside former, and 30 means for moving said inside former out of the U-ed portion to permit the inward collapse of the U-ed portions, and thereafter holding said inside former to act as an anvil while said compressing means presses said collapsed portions on said anvil to complete the formation of the locked seam, said horn having a resilient part adapted to yield to reduce the perimeter of said horn to ease the ejection of said formed body or tube.

35 3. An apparatus of the character described, comprising a horn around which a piece of sheet metal is adapted to be wrapped with ends overlapping, an inside former and an outside former adapted to bend the overlapped portions of the piece of sheet metal into U or channel form, and means for compressing said U-ed overlapped portions while held by said outside former, said inside former being movable out of the U-ed portion to permit the inward collapse of the U-ed portions, and the consequent formation 40 of a locked seam, and wing folders adapted to wrap said piece of sheet metal around said horn.

45 4. An apparatus of the character de-

scribed, comprising a horn around which a piece of sheet metal is adapted to be wrapped with ends overlapping, an inside former and an outside former adapted to bend the overlapped portions of the piece of sheet metal into U or channel form, and means for compressing said U-ed overlapped portions while held by said outside former, said inside former being movable out of the U-ed portion to permit the inward collapse of the U-ed portions, and the consequent formation 50 of a locked seam, wing folders adapted to wrap said piece of sheet metal around said horn, and means adapted to hold said folded sheet metal against said horn during the initial period of the receding movement of said wing folders.

5. An apparatus of the character described, comprising a horn around which a piece of sheet metal is adapted to be wrapped with ends overlapping, an inside former and an outside former adapted to bend the overlapped portions of the piece of sheet metal into U or channel form, and means for compressing said U-ed overlapped portions while held by said outside former, said inside former being movable out of the U-ed portion to permit the inward collapse of the U-ed portions, and the consequent formation 55 of a locked seam, wing folders adapted to wrap said piece of sheet metal around said horn, and means adapted to hold said folded sheet metal against said horn during the initial period of the receding movement of said wing folders, said holding means comprising resiliently mounted presser pieces on said wing folders.

6. An apparatus of the character described, comprising a horn around which a piece of sheet metal is adapted to be wrapped with ends overlapping, an inside former and an outside former adapted to bend the overlapped portions of the piece of sheet metal into U or channel form, and means for compressing said U-ed overlapped portions while held by said outside former, said inside former being movable out of the U-ed portion to permit the inward collapse of the U-ed portions, and the consequent formation 60 of a locked seam, wing folders adapted to wrap said piece of sheet metal around said horn, said U-ed portion compressing means comprising a resiliently mounted hammer, and means adapted to move said hammer into position to hold the lapped ends of said sheet in lapped position prior to the bending action thereon of said formers.

7. An apparatus of the character described, comprising a horn around which a piece of sheet metal is adapted to be wrapped with ends overlapping, an inside former and an outside former adapted to bend the overlapped portions of the piece of sheet metal into U or channel form, and means for com- 70 75 80 85 90 95 100 105 110 115 120 125 130

pressing said U-ed overlapped portions while held by said outside former, and means comprising a cam slide engaging said inside former for moving said inside former in and out of said outside former.

8. An apparatus of the character described, comprising a horn around which a piece of sheet metal is adapted to be wrapped with ends overlapping, an inside former 10 and an outside former adapted to bend the overlapping portions of the piece of sheet metal into U or channel form, means for compressing said U-ed overlapped portions while held by said outside former, and means 15 comprising a cam slide engaging said inside former for moving said inside former in and out of said outside former, said inside former being partially housed in said horn, and said cam-slide being mounted in said horn.
- 20 9. An apparatus of the character described, comprising a horn around which a piece of sheet metal is adapted to be wrapped with ends overlapping, an inside former and an outside former adapted to bend the overlapped portions of the piece of sheet metal into U or channel form, and means for compressing said U-ed overlapped portions while held by said outside former, said in-

side former being movable out of the U-ed portion to permit the inward collapse of the 30 U-ed portions, and the consequent formation of a locked seam, and means for bending one edge of the sheet prior to reaching said horn, whereby said edges may readily overlap when said sheet is wrapped around the horn. 35

10. An apparatus of the character described, comprising a horn, wing folders adapted to wrap a piece of sheet metal around said horn, and means on said wing folders adapted to hold said folded sheet 40 metal against said horn during the initial period of the receding movement of said wing folders.

11. An apparatus of the character described, comprising a horn, wing folders 45 adapted to wrap a piece of sheet metal around said horn, and means on said wing folders adapted to hold said folded sheet metal against said horn during the initial period of the receding movement of said 50 wing folders, said means comprising resiliently mounted presser pieces.

In witness whereof, I have hereunto signed my name.

PETER KRUSE.
